US00D835521S

(12) **United States Design Patent** (10) Patent No.: **US D835,521 S**
Berthier (45) Date of Patent: **** Dec. 11, 2018**

(54) **WATCH**

(71) Applicant: **LA MONTRE HERMES S.A.**, Brugg (CH)

(72) Inventor: **Marc Berthier**, Paris (FR)

(**) Term: **15 Years**

(21) Appl. No.: **35/503,520**

(22) Filed: **Aug. 1, 2017**

(80) **Hague Agreement Data**

Int. Filing Date: **Aug. 1, 2017**

Int. Reg. No.: **DM/097213**

Int. Reg. Date: **Aug. 1, 2017**

Int. Reg. Pub. Date: **Aug. 18, 2017**

(51) **LOC (11) Cl. 10-02**

(52) **U.S. Cl.**

USPC **D10/32**

(58) **Field of Classification Search**

USPC D10/30-32, 38-39, 125

See application file for complete search history.
